ELECTRICAL CONDUCTOR

Ronald J. Kilburg, Belmont, Calif., assignor to
The Rucker Company, Oakland, Calif.

Filed Oct. 30, 1974, Ser. No. 519,100

Term of patent 14 years

Int. Cl. D13—03

U.S. Cl. D26—1 A

FIG. 1 is a perspective view of an electrical conductor showing my new design, with the center broken away to indicate indeterminate length;

FIG. 2 is a fragmentary top perspective view thereof;
FIG. 3 is a fragmentary bottom perspective view thereof; and

FIG. 4 is an end elevation view thereof.

I claim:

The ornamental design for an electrical conductor, as shown and described.
